(57) **CLAIM**

The ornamental design for a shooting bag, as shown and described.

DESCRIPTION

FIG. 1 is an isometric view of my ornamental design for a shooting bag.

FIG. 2 is a front elevational view thereof.

FIG. 3 is a side elevational view thereof.

FIG. 4 is a rear elevational view thereof.

FIG. 5 is a side elevational view thereof.

FIG. 6 is a top plan view thereof.

FIG. 7 is a bottom plan view thereof.

FIG. 8 is a front elevational view shown with the straps in an alternate position.

FIG. 9 is a top plan view of FIG. 8.

FIG. 10 is a side elevational view of FIG. 8.

FIG. 11 is a reduced front elevational view shown with the straps in another alternate position; the unclaimed rifle shown as environmental structure.

FIG. 12 is a reduced side elevational view shown with the straps in another alternate position; and,

FIG. 13 is a reduced side elevational view shown with the straps in another alternate position.

The broken lines in these drawings serve to illustrate the environment in which the claimed design is associated or serve to define the bounds of the claimed design. The broken lines form no part of the claimed design.
